UNITED STATES PATENT OFFICE.

ANDERSON W. HARRIS, OF NORTH CHATTANOOGA, TENNESSEE.

STEAM BOILER.

Application filed February 21, 1923. Serial No. 320,411.

To all whom it may concern:

Be it known that I, ANDERSON W. HARRIS, a citizen of the United States, residing at North Chattanooga, in the county of Hamilton and State of Tennessee, have invented certain new and useful Improvements in Steam Boilers, of which the following is a full, clear, and exact specification.

This invention relates to inverted refractory arches for protecting the girth seams and other parts of the shells of return tubular and other types of steam boilers.

While one of the main objects of the invention is to protect the girth seams of boiler shells, other objects are to utilize the inverted arches for promoting more complete combustion and for replacing the overhanging front walls commonly used for protecting the front ends of such shells, and to provide for circulating water through the supports for said arches so that said supports and said arches will last longer than they would otherwise. In order to promote combustion the arches are arranged at intervals along the boiler shell and in front and rear of the bridge wall, so that the gases or products of combustion must travel a tortuous passage resulting in a more complete mixing thereof with the air than is possible when the arches cover the entire bottom of the boiler shell. The arches according to the present invention are accordingly placed in such a manner as to serve as an ignition or coking arch over the furnace and also to promote the consumption of smoke while increasing combustion.

The overhanging front walls commonly used at the front of boiler settings are a source of annoyance and expense to keep up and when not kept up the gases will be short-circuited in what is known as a flush ended boiler, and in the case of a shell extension boiler the extended part of the shell is left unprotected and is apt to burn and crack, said cracks often extending back beyond the front head and seriously damaging the boiler. By utilizing a water cooled inverted arch in place of an overhanging front wall in accordance with the present invention the annoyance and trouble referred to is avoided because such arch will outlast many overhanging front walls.

Another object of this invention is to improve the construction of the sections or tiles composing the refractory inverted arches and to simplify the mode of sup-

porting them in place, so that a section of an arch or a complete arch may be renewed from time to time as may be required without employing skilled labor. The design 60 and arrangement of the tiles is such that they may expand and contract without causing strains on the boiler shell or the water circulating pipes on which said tiles are supported. 65

A further object is to promote the circulation of water from the boiler shell through the supports for the arches without reducing the efficiency of the shell to an undesirable extent. Other objects will appear 70 as the description proceeds.

The invention will be first hereinafter described in connection with the accompanying drawings, which constitute part of this specification, and then more specifically defined in the claims at the end of the description. 75

In the accompanying drawings, wherein similar reference characters are used to designate corresponding parts throughout the 80 several views:—

Figure 1 is a side elevation of a return tubular boiler shell with the setting for said shell and the arches arranged in accordance with this invention shown in section, the 85 rear end of the shell being broken away.

Figure 2 is a section on the line II—II of Figure 1.

Figure 3 is a detailed section through the shell and one of the arches on an enlarged 90 scale to illustrate the way in which the sections or tiles of said arch are formed to allow for expansion and contraction, and

Figure 4 is a broken view of the front end portion of a shell extension boiler with 95 its setting and an arch to replace the usual overhanging portion of the front wall shown in section.

Referring first to Figures 1, 2 and 3 of the drawings, 1 designates the shell of a return 100 tubular steam boiler which may have any number of girth seams 2, one of which is shown at an intermediate point and another at the front end of the shell which in this instance is of the flush ended type. The 105 setting of the boiler may or may not have the usual bridge wall 3 at the rear end of the grate 4.

Each of the refractory inverted arches 5, of which six are shown in Figure 1, comprises a plurality of tiles, blocks or sections 6 made of suitable heat resisting or refrac-

2

tory material and formed generally hook-shaped with a notch 7 opening on its upper surface and extending below an overhanging lug or extension 8 having a substantially 5 horizontal or slightly curved under face adapted to engage and hang over a water pipe 9 by which the arch is supported in position under the boiler shell. The water pipe 9 for each arch extends concentric to the 10 boiler shell and communicates with the interior of said shell at opposite sides thereof on different levels, as shown best in Figure 2, so as to create an unequal head of water and cause circulation of some of the water 15 from said shell through said pipe. Thus, the connection 9^a of each water pipe on one side of the shell is higher than the connection 10 of said pipe with the other side of the shell, but both connections are preferably 20 below the water line of the shell. This circulation of the water from the shell through the supporting pipes 8 of the arches 5 protects the metal in the supports from overheating, thereby greatly increasing the durability 25 of the arches as compared with those mounted on supports through which water is not circulated. When a plurality of arches are used, as shown in Figures 1 and 2, the supporting pipes 9 therefor have alternating high and low connections to the shell on both sides so as not to reduce the efficiency 30 of the shell to an undesirable extent by having holes in same spaced too close together on the same line.

35 The tiles 6 are formed as shown so that one end of each of them is normally spaced from the shell at 11, Figures 1 and 3, while the upper face of the overhanging lug or extension 8 of each tile is inclined at 12 so 40 that only the end portion of the tile adjacent said lug normally contacts with said shell, leaving room for said tiles to rock on the supporting water pipes under expansion or contraction without placing strains on the shell or pipes. It will be noted also that 45 the tiles are simply hung on or over the supporting pipes, no bolts being used for binding said tiles to the pipes or to the shell, so that it is an easy matter for unskilled workmen to remove and replace the tiles in a portion of an arch or in an entire arch whenever required. Furthermore, the absence of bolts piercing the shell for fastening 50 the sections of the arches thereto is an important improvement over prior constructions because the tapped holes for said bolts tend to weaken the shell.

The arches 5 are placed so as to protect 55 the girth seams from the direct action of the fire, and at the front end of the shell the arch which protects the end seam takes the place of the usual overhanging wall in the extension shell type of boiler illustrated in Figure 4 as well as in the flush ended type 60 shown in Figure 1. In Figure 4 the parts

shown are designated by the same reference characters as in Figure 1, the extension end of the shell being indicated at 13, in Figure 4, while the flush end or head of the boiler shell in Figure 1 is indicated at 14.

The arches 5 may also be placed at suitable intervals along the bottom of the shell to form ignition or coking arches and compelling the gases or products of combustion to travel a tortuous passage under said shell so as to cause said gases to become thoroughly mixed with the air to the end that complete combustion may be promoted and the smoke consumed. As shown in Figure 1, one or more of the arches may be 70 placed in front and in rear of the bridge wall 3, and if desired, said arches may also be placed over the bridge wall. A plurality of said arches may also be arranged over the front portion of the firebox adjacent 75 the one protecting the end seam of the boiler seam and which may overlap the front wall of the setting to some extent, as shown in Figures 1 and 4. Said arches may indeed 80 cover the entire firebox, if desired. It will be understood, however, that other variations may be made in the arrangement of the arches shown and described herein so that 85 they will protect weak points, such as bags or patches on the boiler shell, without departing from this invention.

If desired, the supporting pipe 9 for the arches may communicate with the interior of the shell, as indicated at 15 in Figure 2, but the connection of the ends of said pipes 100 with the shell may be sufficient and preferred. It will further be understood that the term "tiles" used in this specification and in the claims appended hereto is intended to include blocks, bricks and any other sections 105 of the arches no matter of what kind of refractory material they may be made.

I claim:

1. The combination with a boiler shell, of an inverted refractory arch for protecting a 110 portion of its under surface, said arch comprising a support spaced from the shell and a series of refractory tiles each having a notch in its upper face and a lug overhanging one end portion of said notch and extending between the support and shell, the upper edge of said lug being inclined and the inner end of said lug and the other end of the tile being normally spaced from the shell, whereby said tiles may rock on the 115 support under expansion or contraction for the purpose specified.

2. The combination with a boiler shell, of an inverted refractory arch for protecting a 120 portion of its under surface, said arch comprising a support spaced from the shell, and a series of refractory tiles each having a notch in its upper face and a lug overhanging one end portion of said notch and extending between the support and shell, the 125

other end of each tile extending upward above said support to a point adjacent the boiler shell.

3. The combination with a boiler shell, of an inverted refractory arch for protecting a portion of its under surface, said arch comprising a tubular support spaced from the shell and a series of refractory tiles each having a notch in its upper face and a lug 10 overhanging one end portion of said notch and extending between the support and shell, the upper edge of said lug being inclined and the inner end of said lug and the other end of the tile being normally spaced from 15 the shell, whereby said tiles may rock on the

support under expansion or contraction, and means for circulating water from the shell through said tubular support.

4. In a device of the class described, a support, a tile for said support comprising a 20 body having an inclined upper face, an angularly disposed notch entering said face and terminating nearer one end thereof than the other, said notch providing an overhanging lug, and the breadth of said notch beneath said lug being greater than the breadth of said support. 25

In testimony whereof I have signed my name to this specification.

ANDERSON W. HARRIS.
